100,818

DESIGN FOR A COMBINED FAN BLADES AND HUB UNIT

Alfred C. Gilbert, Hamden, and John Lanz, New Haven, Conn., assignors to The A. C. Gilbert Company, New Haven, Conn., a corporation of Maryland

Application March 29, 1935, Serial No. 56,111

Term of patent 14 years

To all whom it may concern:

Be it known that we, Alfred C. Gilbert and John Lanz, citizens of the United States, residing, respectively, at Hamden, in the county of New Haven and State of Connecticut, and at New Haven, in the county of New Haven and State of Connecticut, have invented a new, original, and ornamental Design for a Combined Fan Blades and Hub Unit, of which the following is a specification, reference being had to the accompanying drawing, forming part thereof.

Figure 1 is a front view, and Figures 2, 3, 4 and 5 are sides views, looking respectively in the directions of arrows 2, 3, 4, and 5, of a combined fan blades and hub unit, showing our new design.

The present design comprises as distinctive and prominent features thereof, four thin scoop-like blades so arranged about a common hub that substantially the entire front surface and/or the entire rear surface of one or more of the blades is fully exposed to view from the front and/or

side, each of which blades has a front surface of continuous concavity and a rear surface of continuous convexity throughout the whole surface of the blade, and each of which blades has edges so contoured that the foreshortened shape of the full surface of the blade when projected in the direction of the axis of the hub and also when projected in directions perpendicular to said axis is that of a figure resembling in general a crescent and outlined by two flaring curves which meet and form a relatively narrow and pointed end of the projected figure and by a third curve which connects the two flaring curves and forms a relatively large and generously rounded opposite end of the projected figure.

We claim:

The ornamental design for a combined fan blades and hub unit, as shown and described.

ALFRED C. GILBERT.
JOHN LANZ.
